UNITED STATES PATENT OFFICE.

STEVE FODOR, OF ORIENT, ILLINOIS.

BURGLAR ALARM.

Application filed January 6, 1923. Serial No. 611,064.

To all whom it may concern:

Be it known that I, STEVE Fodor, a citizen of Hungary, residing at Orient, in the county of Franklin and State of Illinois, have invented certain new and useful Improvements in Burglar Alarms, of which the following is a specification.

This invention relates to new and useful improvements in burglar alarms and further provides a protection against such intruders.

An important object of the invention is to provide a device suitable for use as a protection against bank robbers as well as for sounding an alarm.

A further object of the invention is to provide a device of the above mentioned character that is controlled by the bank cashier or tellers for performing its desired function and wherein the device will be automatically reset for repeated use.

A further object is to provide means for actuating a device of the above character and wherein the control for said means may be modified to adapt the device for many uses without materially changing the construction of the device or its actuating means.

A further object of the invention is to provide a device that is simple in construction, reliable in operation, strong, and durable.

Other objects and advantages of the invention will be apparent during the course of the following description.

In the accompanying drawing forming a part of this specification and in which like numerals are employed to designate like parts throughout the same,

Figure 1 is a front elevational view of a portion of the interior of a bank and shows teller window with the device associated therewith and indicated in dotted line,

Figure 2 is a top plan view of the device with the casing in section to better show its contents, and further shows a source of electrical energy and its controlling means,

Figure 3 is an elevational view with the casing in section to display the side of the device, and

Figure 4 is a modification of the controlling means for the electrical supply.

Referring to the accompanying drawing, and more particularly to Fig. 1, there is shown the usual partition constituting the front of bank teller cages with the usual

windows 1 formed therein. The device, as indicated in dotted lines, is preferably positioned rearwardly of the said partition and below the counter portion 2. There is further provided a small inconspicuous opening 3 through which the bullets from the device are allowed to pass when the apparatus is used as a protection against bank robbers.

Referring particularly to Figs. 2 and 3 there is shown the preferred embodiment of the invention and consists of a box or casting that is adapted to house the device, with the exception of the electric wiring and its controlling means. It is to be understood that the mounting or support for this box may be varied to suit the occasion, and, therefore, does not enter into the spirit of this invention. This box embodies a bottom wall 4, side walls 5, and end walls 6 and 7, while the top of the box is closed by the cover 8. The end wall 6 is provided with an opening 6' through which the outer end of the pistol barrel 9 slightly projects. The end of the barrel is further supported as by the bracket member 10 that encircles the barrel and conforms in shape therewith. This bracket member is provided with laterally extending arms 11 that are adapted to be secured to the end wall 6 by the screws 12. Secured to the bottom wall 4 is a block 13 that is provided with a pocket 14 that conforms in shape with the lower end of the hand grip 15 and is adapted to rigidly support the same and be secured thereto by means of the screw 16.

It is preferred that the usual trigger guard be removed to better enable the trigger operating means to be properly associated with the trigger 17. Rigidly secured to the bottom walls are spaced perpendicular blocks 18 that are positioned laterally of the trigger 17 and are provided with elongated slots 19 that are in horizontal alignment with the said trigger. Slidably mounted within the elongated slots 19 is a soft iron armature 20 that is provided with rings 21 suitable for engaging the outer faces of the blocks 18 for retaining the armature 20 against longitudinal movement. Secured to the bottom wall 4, and spaced forwardly from the armature 20 are perpendicular posts 22 having springs 23 secured thereto adjacent their upper ends and extending rearwardly to be secured to the armature 20 as shown. It is to be under-

stood that the springs 23 are provided to normally retain the armature 20 against the forward end of the elongated slots 19.

The operating means for the armature 20 consists of a pair of magnets 24 that are adapted to be mounted upon the poles 25 of the horseshoe magnet 26. This horseshoe magnet is secured to the end wall 7 by means of the bosses 27 and screws 28. It will be seen in Fig. 2 that the outer ends of the poles 25 are spaced from the armature 20 when the latter is retained at the outer ends of the elongated slot 19. A battery 29 is provided for supplying current to the electric magnets 24 through the circuit wires 30. The controlling means for this electric circuit consists in this embodiment of the invention of a lever arm 31 that is adapted to be moved into and out of engagement with the contact member 32.

Referring to Fig. 4 there is shown a modification of the circuit closing means which consists of a pedal member 33 that is pivotally mounted to the support 34 and is provided with a contact member 35 that is normally retained spaced from the contact member 36 by the spring 37. It is to be understood that the balance of the device is identical with the form shown in Figs. 2 and 3, but the modification of the circuit controlling means is intended to suggest the numerous adaptations of the device for various purposes without materially changing the construction of the box and its contents.

It is believed that the operation of the device will be apparent from the above description, but special attention is called to the following features of construction. It is to be understood, although the device is shown herein as a protection against bank robbers, that the device may as readily be mounted adjacent doors or windows of a house and that the circuit closing means may be modified to operate the device when the said doors or windows are opened by unauthorized persons. A further suggestion for a modification of the circuit closing means is to construct the same in the form of a treadle that is positioned inwardly of a door frame and adapted to be stepped upon

by an intruder after he has gained admission through the door.

In the operation of the device, it is to be understood that the armature 20 operatively engages the trigger 17 when in its normal position and that when the circuit closing means is operated to energize the magnets 24 the said armature will be attracted by the poles 25 and moved thereagainst to operate the trigger for firing the pistol. It will be seen that upon breaking the circuit the springs 23 will return the armature 20 to its normal position in readiness for repeating the operation and that the entire contents of the pistol may be discharged therefrom by repeatedly opening and closing the circuit to the said magnets.

It is to be understood that the form of this invention herewith shown and described is to be taken as the preferred example of the same, and that various changes in the shape, size, and arrangement of parts may be resorted to without departing from the spirit of the invention or the scope of the subjoined claim.

Having thus described the invention, I claim:

In a device of the character described, a casing having an opening, a pistol in said casing having its barrel projecting through said opening, a bracket secured to said casing for supporting said barrel, a block mounted in said casing for supporting the hand grip of said pistol, perpendicular blocks having slots formed therein secured to said casing on opposite sides of the trigger for said pistol, an armature positioned in said blocks traversing said trigger forwardly thereof for operative engagement therewith, electromagnets positioned on opposite sides of said casing for attracting said armature to operate said trigger, means for energizing said magnets, a circuit closing means associated therewith positioned exteriorly of said casing, and means within said casing for returning said armature to its starting position after having operated said trigger.

In testimony whereof I affix my signature.
STEVE FODOR.
